UNITED STATES PATENT OFFICE.

JACOB KARR, OF WASHINGTON, DISTRICT OF COLUMBIA.

DESIGN FOR A SPOON, &c.

SPECIFICATION forming part of Design No. 20,823, dated June 9, 1891.

Application filed May 6, 1891. Serial No. 391,825. Term of patent 7 years.

To all whom it may concern:

Be it known that I, JACOB KARR, a citizen of the United States, residing at Washington, in the District of Columbia, have invented 5 and produced a new and original Design for the Handles of Spoons, Forks, and Similar Articles, of which the following is a specification.

The annexed drawing shows a plan view of 10 a spoon, illustrating my design.

My invention is a design for the handles of "souvenir" spoons; and it consists, essentially, of a fasces forming the greater portion of the handle and surmounted by a wreath.

15 In the drawing, A designates the bowl of the spoon, and B the handle thereof. At the junction of the bowl and the handle is a scroll C, forming a base, from which rises a column D, which is represented as a fasces composed

of a number of rods E, bound together by 20 ribbons or bands F. The upper end of the column or fasces is lost in a wreath G, which surrounds an initial letter, and above which appears a bust, the junction of the bust and the wreath being ornamented by a scroll H. 25

Having thus described my invention, what I claim, and desire to secure by Letters Patent, is—

The design for the handles of spoons, forks, and similar articles herein described and 30 shown.

In testimony whereof I affix my signature in the presence of two witnesses.

JACOB KARR.
